UNITED STATES PATENT OFFICE

LORENZ IVERSEN, OF PITTSBURGH, PENNSYLVANIA, ASSIGNOR TO MESTA MACHINE COMPANY, OF PITTSBURGH, PENNSYLVANIA, A CORPORATION OF PENNSYLVANIA

ROLLING MILL

Application filed July 10, 1926. Serial No. 121,614.

The present invention relates broadly to the art of metal rolling, and more particularly to improvements in rolling mills, and especially rolling mills of the character usually designated as four-high mills, and to cluster mills.

At the present time it is customary in the art to which this invention relates to construct four-high mills in which both the smaller intermediate rolls are driven as well as the lower roll. For the purpose of driving the lower roll it is customary to provide a special pinion in the gear housing and connect the same with the lower roll through a slip or friction drive. It will be apparent that such a construction not only increases the cost of the installation but also the expense of upkeep. The slip driving connection is also objectionable from the standpoint of difficulty in adjustment for satisfactory operation.

The present invention has for one of its objects the provision of an improved mill of such nature that the rotation of the lower roll of a four-high mill or the rotation of the lower rolls of a cluster mill is insured without the provision of any special driving means therefor.

Another object of the present invention is to provide a rolling mill having improved means for balancing the upper rolls, the construction preferably being such that the weight of all of the upper rolls is transmitted directly to the lower roll or rolls for improving the frictional drive of such lower roll or rolls.

In the accompanying drawings I have shown more or less diagrammatically, for purposes of illustration only, a preferred embodiment of the present invention, it being understood that the drawings do not define the limits of my invention as changes in the construction and operation disclosed therein may be made without departing either from the spirit of the invention or the scope of my broader claims.

In the drawings,

Figure 1 is an end elevational view, partly broken away, illustrating one form of mill embodying the present invention,

Figure 2 is a vertical sectional view along the line II—II of Figure 1, certain of the parts being shown in elevation for the sake of clearness, and

Figure 3 is a diagrammatic view showing a cluster mill.

In carrying out the present invention there may be provided a mill housing 2 of any desired construction having windows 3 therein through which may extend the necks 4 of the upper and lower or backing rolls and the necks 5 of the intermediate or working rolls.

For driving the working rolls there is shown a pinion housing 6 having pinions 7 therein adapted to drive the spindles 8 connected in known manner to the intermediate rolls.

It is obviously desirable in mills of the four-high type to insure continuous rotation of the lower backing roll at all times while the mill is in operation. Heretofore, such rotation has been obtained by reason of a special slip or driving connection. In accordance with the present invention the necessity of such a connection is obviated by an improved mounting of the rolls in such manner that the weight of at least two, and preferably of all of the top three rolls, is transmitted directly to the lower roll for insuring such a frictional contact therewith that the lower roll will be continuously driven by friction during the operation of the mill. The desired results herein contemplated may be obtained by providing at each end of the housing a special yoke for the working rolls, each of which yokes comprises a lower section 9 and an upper section 10. Each of these sections carries one of the working rolls, and the desired balancing action is obtained by providing the lower section with holders 11, preferably of generally cylindrical cross-section adapted to receive compression springs 12. These springs at their lower ends bear against the bottoms of the holders and at their upper ends contact with followers 13 engaged by adjusting screws 14. Each of the adjusting screws may be located in position in any desired manner, as for example, by a lock nut 15, whereby any desired initial compression may be exerted on the springs.

100

for thereby insuring the proper balancing action.

Inasmuch as the bottom one of the working rolls rests directly on the lower roll, it will be apparent that the weight of this bottom working roll is carried by the lower roll. Also, in view of the yoke construction and arrangement, the weight of the top one of the working rolls is likewise transmitted to the lower roll. Lateral movement of the yoke sections either transversely with respect to the housings or outwardly with respect thereto may be prevented by suitable guiding clamps 16.

The upper backing roll is conveniently mounted at its opposite ends in bearings 17 having slots 18 accommodating holding bolts 19 whereby the top roll may be vertically adjusted at will by suitable screw down mechanism 20 as well understood in the art. The construction of the screw down mechanism and of the bearing 17 is such that the weight of the upper roll is also carried by the intermediate rolls and in turn through them by the lower roll. With such an arrangement the weight of the upper rolls is sufficient to insure frictional contact between the bottom intermediate roll and the lower roll of such nature that continuous rotation of the lower roll is insured. This constitutes one of the advantages of the present invention.

As illustrated in Figure 3 the invention is also applicable to a cluster mill, the weight of the working rolls *w* in such case being transmitted to the two bottom backing rolls *b* for insuring rotation thereof by friction.

A further advantage of the present invention arises from the provision of a yoke of such nature that the weight of at least the two intermediate rolls, and preferably of the two intermediate rolls and of the upper roll may be transmitted directly to the lower roll or rolls.

Still further advantages of the invention arise from the provision of an improved balancing means, preferably in the form of a spring, so mounted that the thrust exerted in the balancing action is transmitted directly to the lower roll or rolls and not to the mill housing as has heretofore been customary.

I claim:

1. In a mill, upper and lower backing means, intermediate rolls, and spring means for supporting one of the intermediate rolls from the other and for transmitting the weight of the upper backing means to the lower backing means.

2. In a mill, at least one lower undriven backing roll, at least one upper backing roll, upper and lower working rolls intermediate the backing rolls, means for driving the working rolls, the lower backing roll supporting the lower working roll, and spring means connecting the upper and lower working rolls and effective for transmitting the weight of

the upper working roll and the upper backing roll to the lower working roll.

3. In a mill, at least one lower undriven backing roll, at least one upper backing roll, upper and lower working rolls intermediate the backing rolls, means for driving the working rolls, the lower backing roll supporting the lower working roll, yoke portions carried on the necks of the lower working roll, yoke portions carried on the necks of the upper working roll, spring means interposed between the yoke portions, and means for adjusting the spring pressure.

4. In a mill, intermediate rolls, a yoke common to said rolls, and roll balancing means carried by said yoke, said roll balancing means comprising a spring and means for adjusting the pressure thereof.

5. In a mill, intermediate rolls, a yoke common to said rolls, and roll balancing means carried by said yoke, said roll balancing means comprising a plurality of springs, each provided with means for adjusting the spring pressure.

6. In a mill, a mill housing, a lower backing means in said housing, intermediate rolls, upper backing means, and yielding means tending to separate the intermediate rolls, the last mentioned means being effective for transmitting the weight of the upper backing means to the lower backing means.

In testimony whereof I have hereunto set my hand.

LORENZ IVERSEN.
